UNITED STATES PATENT OFFICE.

ARTHUR FREDERICK RICHMOND COTTON, OF LONDON, ENGLAND.

DIAPHRAGM.

1,417,718.

Specification of Letters Patent. Patented May 30, 1922.

Application filed February 8, 1921. Serial No. 443,331.

To all whom it may concern:

Be it known that I, ARTHUR FREDERICK RICHMOND COTTON, a British subject, residing at 1^a Chesterfield Street, Mayfair, London, England, have invented certain new and useful Improvements in Diaphragms, of which the following is a specification.

This invention relates to vibratory diaphragms for telephone receivers, for the sound boxes of gramophones and the like, and for other similar purposes, and consists of an improved diaphragm suitable both for the preparation of sound records and for the reproduction of sound by records or other means. The main object is to provide a diaphragm with no musical note or frequency of its own and thereby to eliminate resonance effects due to the actual material of the diaphragm.

According to the present invention, the disc forming the diaphragm is composed of one or more layers of woven or other fabric of textile material which is or are stiffened by impregnation with celluloid by means of a suitable solvent of the latter.

The invention is hereafter more fully described with reference to the accompanying drawings, in which:—

Figures 1 and 2 represent suitable discs of linen and celluloid respectively for the construction of the diaphragm.

Figures 3 and 4 show sections of the juxtaposed discs ready for pressure.

Figure 5 illustrates a frame holding the textile material before application of the celluloid disc.

Figure 6 represents in section the completed diaphragm ready for mounting.

Figure 7 is an elevation of a completed diaphragm suitable for a telephone receiver.

Figure 8 is a section of the same.

Figure 9 is an elevation of a diaphragm for the soundbox of a gramophone.

Figure 10 is a part sectional elevation of the diaphragm fitted in the soundbox.

The improved diaphragm A comprises a foundation consisting of a textile fabric, which may be of cotton, muslin, linen or silk, and is stiffened by impregnation with celluloid. The fabric may be woven as shown by the disc a in Figure 1, or may consist of superposed layers a¹ a² of parallel threads, as shown in Figure 5, where the two layers merely cross one another. I have ob-

tained the best results by employing a woven 55 linen fabric of the kind known as tracing cloth.

The fabric is cut into discs a of suitable size, and is applied to a celluloid sheet or disc b preferably thicker (Figure 2), which 60 is treated with aeroplane dope, acetone or like solvent; the two juxtaposed materials (see Figure 3) are preferably subjected to slight pressure, whereby the softened celluloid is caused to penetrate the textile material. 65 The solvent is then removed, its departure being accelerated by artificial drying if desired.

Alternatively the linen or like material may be stretched in a suitable frame c as 70 shown in Figure 5, in which it is gripped around the periphery by means of clamping nuts c¹ pressing upon a cover plate c²; the solvent is then applied and the celluloid disc b is pressed into contact with the fabric, as 75 indicated in Figure 3. The celluloid discs may be applied on both sides of the fabric a if desired, as shown in Figure 4. In either case the softened celluloid is caused to penetrate the fabric, resulting in an adherent 80 structure, the section of which is shown in Figure 6.

In the case of a telephone receiver, the centre of the diaphragm A is provided with means for electromagnet operation, such as 85 a disc d of soft iron, as seen in Figure 7, to form a magnetic armature suitably secured in position by a rivet d¹ and washer d² (Figure 8).

For gramophone sound boxes and the like, 90 the stylus bar e is connected to the impregnated linen diaphragm A (Figure 9) by means of two washers or nuts e¹ e² upon a central pin or rivet e³ passing through the diaphragm, as shown in Figure 10, or by means of a screw which pierces the diaphragm and is secured to the stylus bar. 95

I have found by experiment that diaphragms constructed as above described possess a number of advantages over diaphragms as heretofore usually made, for example of mica, amongst which advantages may be mentioned reduction of cost, less liability of damage, and the facility to reproduce sound without the grating or scratching noises which usually accompany such reproductions with gramophone diaphragms of the ordinary type. By using celluloid of 100 105

greater thickness than the textile the latter becomes entirely immersed within the celluloid.

Having thus described my invention, what I claim as such and desire to secure by Letters Patent is:—

1. A vibratory diaphragm, composed of textile fabric stiffened by impregnation with celluloid by means of a solvent of the latter.
  - 10 2. A vibratory diaphragm composed of linen applied to a sheet of celluloid which is treated with a solvent of the latter and caused to penetrate the fabric.
  - 15 3. A vibratory diaphragm, composed of textile fabric and celluloid, said celluloid being caused to impregnate said fabric.
  - 20 4. A vibratory diaphragm, composed of textile fabric and celluloid, said celluloid being softened by means of a solvent and while thus softened caused to impregnate said fabric.
  5. A vibratory diaphragm, comprising a foundation of textile material and a layer
- of celluloid, said celluloid covering the face of said textile material and also penetrating 25 thereinto.
6. A vibratory diaphragm, consisting of a foundation of textile material, and a covering of celluloid, said celluloid being treated with a solvent and caused to impregnate said 30 textile material, being thereafter freed from said solvent by evaporation caused by drying.
  7. A diaphragm for the soundboxes of gramophones, comprising a disc made of 35 tracing linen, layers of celluloid applied to both sides of said disc, said layers of celluloid being treated with aeroplane dope and subjected to pressure against said disc.

In testimony whereof I hereunto affix my 40 signature.

ARTHUR FREDERICK RICHMOND COTTON.
